(57) **CLAIM**

The ornamental design for a thermal transfer apparatus, as shown and described.

DESCRIPTION

FIG. 1 is a front perspective view of a thermal transfer apparatus;

FIG. 2 is a front elevational view of the thermal transfer apparatus of FIG. 1;

FIG. 3 is a rear elevational view of the thermal transfer apparatus of FIG. 1;

FIG. 4 is a left side elevational view of the thermal transfer apparatus of FIG. 1;

FIG. 5 is a right side elevational view of the thermal transfer apparatus of FIG. 1;

FIG. 6 is a top view of the thermal transfer apparatus of FIG. 1; and,

FIG. 7 is a bottom view of the thermal transfer apparatus of FIG. 1.

The broken lines in the drawings are for the purpose of illustrating portions of the thermal transfer apparatus that form no part of the claimed design.
